UNITED STATES PATENT OFFICE.

ERNEST STUKE, OF MERIDIAN, MISSISSIPPI.

VALVE-OPERATING MECHANISM.

1,357,912.

Specification of Letters Patent. Patented Nov. 2, 1920.

Application filed May 12, 1919. Serial No. 296,609.

To all whom it may concern:

Be it known that I, ERNEST STUKE, a citizen of the United States, residing at Meridian, in the county of Lauderdale and 5 State of Mississippi, have invented a new and useful Valve-Operating Mechanism, of which the following is a specification.

The present invention relates to internal combustion engine valves and operating 10 mechanism therefor, an object being to provide a valve structure wherein a single valve is employed for controlling the passage of 15 the fuel into the engine cylinder, and controlling the exhaust from the same.

15 A second important object of the invention is to provide a valve mechanism and operating means therefor, which is of the reciprocatory type, a single valve being employed for controlling the inlet of fuel 20 into the engine cylinder and the outlet of the exhaust gases therefrom, in conjunction with the usual reciprocatory valve in the head of the cylinder which is closed during the explosive operation therein and which is 25 opened after the explosive operation, both valves being operated by a common operating mechanism.

Another object of the present invention is 30 to provide a valve operating mechanism which necessitates only one timer rod and a single cam for operating the same to operate a valve in the cylinder head and a second valve which controls both the intake and the outlet ports of the cylinder.

35 An additional object is to provide a valve construction of the above character which is simple in construction, which consists of few parts, and which may be manufactured and placed on the market at a minimum cost.

40 With the above and other general objects and advantages in mind, the invention consists of combinations of elements, arrangements of parts, constructions and operations, and general assemblage all of which will be 45 hereinafter fully enlarged upon and illustrated in the accompanying drawings, wherein the preferred types of the invention are shown, the novel features of the invention being defined in the subjoined claims.

50 On the drawings;

Figure 1 is a fragmentary vertical sectional view of an internal combustion engine including the spring-actuated reciprocatory valve, and operating mechanism therefor as 55 constructed in accordance with my invention; and

Fig. 2 is a like view showing a modified valve operating mechanism.

Referring to the drawings in detail and particularly to Fig. 2 which shows the preferred embodiment of the invention, the engine cylinder is indicated at 5 having a common inlet and outlet port 6 and further provided with a valve chamber 7 provided with an inlet port 8 and an exhaust port 9 both of which communicate with the port 6 in the cylinder 5.

A reciprocatory valve 10 is mounted in the cylinder 5 and reciprocates through the stuffing box 11 in the cylinder 5. A second reciprocatory valve 12 is mounted in the valve chamber 7. The washer 13 is secured to the valve stem of the valve 12, while a fixed collar 14, secured to the casting is engaged upon the valve stem and above the washer 13, an expandable coil spring 15 being positioned on the valve stem and interposed between these two washers. The collar 16 is slidably mounted upon the upper end of the valve stem and sits against the fixed collar or brace 14. This collar 16 is normally urged into engagement with the brace 14 through the medium of a second expandable coil spring 17 which encircles the upper end of the valve stem and bears against the collar 18 upon the outer end of the same and which is fixed thereto.

An eccentric 19 is carried by the camshaft of the engine (not shown) which operates an eccentric arrangement 20 carried by a timer or operating rod 21 which is pivotally connected with one end of a valve operating rod 22 as indicated at 23, the forward end of this valve operating rod being pivotally connected with the collar 16.

95 A sleeve 24 is positioned on the bushing 11 and receives the valve rod of the valve 10. Encircling this sleeve 24 is an expandable spring 25 which bears against the bushing 11. A head 26 is formed upon the upper end of the threaded sleeve 24 in which the valve stem 10 is engaged and is provided with a seat 10', the coil spring 25 bearing against this head and urging the valve rod 22 upwardly and seating the valve 10'. A fulcrum 22' is formed in the rod 22 adjacent its forward end and seats in the seat 10' in the head.

100 The operation of the embodiment of the invention above set forth is as follows: The valve 10' being closed, the cam 19, through the medium of the rod 21, moves the rod

22 downwardly and unseats the valve 10². The valve 10² moves downwardly under pressure of rod 22 which abuts the head 26, the rod 22 then rocking upwardly on its fulcrum point slides the collar 16 on the valve stem of the valve 12 to rise upwardly to open the intake 8 and close the exhaust 9 and allow a charge to enter the engine cylinder. At this time the cam 19 becomes inoperative and allows the rods 21 and 22 to resume their initial position, at the same time closing the valve 10². The engine now fires, the valve 10² being operated as above mentioned to allow the exhaust gases 15 to escape.

In the construction shown in Fig. 1 the valve 28' in the engine cylinder is raised by action of cam 33, depressing synchronously coils 31 and 29. A collar 29' is 20 ably mounted upon the stem of this valve and is normally held against the fixed brace 30' by a coil spring 31. An operating rod 27' which connects with the slidable collar 29' is operated by a reciprocable rod 32 and 25 a cam 33. The valve 12' which controls the intake and exhaust, in this instance is operated by means of the arm 13', which has one of its ends contacting with the head 14' positioned on the upper end of the valve 30 member 12', the coiled spring 16' being provided for the purpose of normally closing the valve member 12'. This arm 13' is 35 operated by any suitable cam mechanism not shown, but which cam mechanism is similar to that shown for operating the rod 27' of this figure.

This disclosure is merely illustrative and it is to be understood that the invention is susceptible to various modifications, and that 40 the limits of such modification are governed by what is claimed.

What is claimed is:—

1. In a valve operating mechanism for internal combustion engines, an engine cylinder having a common intake and exhaust port, and further provided with an intake port and an exhaust port which are in communication with the common port, a reciprocable valve for controlling the intake and exhaust ports, a second reciprocable valve mounted in the engine cylinder, a coiled spring encircling the first mentioned valve and normally urging the same to a position to close the intake port, an operating lever 50 having one end slidably and pivotally con-

nected with the upper end of the last mentioned valve, a second coiled spring operatively connected with the lever and urging the same downward, the lever being pivotally connected to the upper end of the last mentioned valve, means for rocking the valve rods, a stop carried by the valve stem to limit the downward movement of the same whereupon the valve rod is rocked to cause the upper end thereof to move upwardly to force the first mentioned valve to move upwardly to close the exhaust port, a coiled spring engaged with the valve stem urging the valve in the engine cylinder to closed position, said valve being opened after the charge has been ignited in the cylinder to permit the exhaust gases to escape before the first mentioned valve is moved to close the exhaust port.

2. In a valve operating mechanism, an engine cylinder having a common inlet and outlet port, a valve casing mounted adjacent the cylinder and provided with an intake port and an exhaust port in communication with the first mentioned port, a valve reciprocable in the casing, a coiled spring encircling the valve and urging the same to a position to close the intake port, a collar slidable upon the stem of the valve, a second expansible spring encircling the stem 85 of the valve and bearing against the collar, a second reciprocable valve arranged in the engine cylinder the stem thereof projecting through the cylinders, a sleeve receiving the stem and positioned upon the cylinder a 90 head formed upon the upper end of the valve stem a rocking operating arm having one end pivotally connected with the collar and adapted to fulcrum on the head adjacent the sleeve and bearing against the head 95 to urge the operating arm upwardly to allow the first mentioned valve to close the exhaust port, cam mechanism for rocking the arm whereupon the valve in the cylinder is opened to permit a charge to enter the 100 same, the head abutting the upper end of the sleeve to cause the arm to be rocked to close the intake port.

In testimony that I claim the foregoing as my own, I have hereto affixed my signature in the presence of two witnesses.

ERNEST STUKE.
